UNITED STATES PATENT OFFICE.

ALANSON McD. GRAY, OF ELIZABETH, NEW JERSEY, ASSIGNOR TO THE M. W. KELLOGG COMPANY, OF NEW YORK, N. Y., A CORPORATION OF DELAWARE.

FILTER PRESS.

Application filed March 8, 1922. Serial No. 542,110.

To all whom it may concern:

Be it known that I, ALANSON McD. GRAY, a citizen of the United States of America, residing at 72 Hazard Place, Elizabeth, New Jersey, am the inventor of certain new and useful Improvements in Filter Presses, of which the following is a true and concise description.

My invention relates to filter presses and has as one of its objects to provide an arrangement whereby the large sized filter presses of standard type may be operated more conveniently and quickly than has heretofore been the case.

The second object of my invention is to provide an arrangement for a standard type filter press whereby large sized filter presses may be manufactured more economically. As is well known, the petroleum industry, as well as other industries, makes use of a filter press comprising a fixed head, a movable head and a large number of blanketed plates alternating with rings and tightly clamped between the fixed and movable heads during the period of operation. Preparatory to taking down the press after a run, it has been the practice to remove certain large heavy nuts from tie rods extending between the two heads in order to withdraw the movable head to permit the removal of the plates and rings for cleaning purposes. Since the movable head lies above the pit, it has been a difficult and tedious job to remove these nuts. Moreover, the limiting weight of the nuts which the workmen could handle under the conditions of operations of this process has been such that the presses have been built with a greater number of tie-rods than need have been the case, thus increasing the cost of the presses.

According to my invention, the nuts and the tie-rods are dispensed with and the movable head and the small key and head arrangement substituted, whereby the movable head may be quickly released when desirable. The parts which the workmen need lift are thus greatly reduced in size and weight with an increase in quickness of operation and the reduction in weight of these parts permits the rods to be made heavier, thus permitting a reduction in their number and reducing the cost of the press.

The novel features of my invention are pointed out with particularity in the appended claims. The invention itself, how-

ever, with further objects and advantages will best be understood by those skilled in the art from the following description taken in connection with the accompanying drawing in which—

Fig. 1 is an elevational view, partly broken away for purposes of illustration, of a portion of a press according to my invention.

Fig. 1^a is a view supplemental to Fig. 1 and illustrating the remainder of the press appearing in Fig. 1.

Fig. 2 is a section on the line 2, 2 of Fig. 1.

Fig. 3 is a detail illustrating two pairs of filter plates and cooperating rings in longitudinal section.

Fig. 4 is a section on the line 4, 4 of Fig. 1.

Fig. 5 is an enlarged detail in section of a tie-rod fitted with an extension head and key in accordance with my invention.

Fig. 6 is a detail plan of the parts shown in Fig. 5.

In the drawing, 1 is a fixed head of a filter press of known type, the parallel cooperating movable head of which is designated by numeral 2. Head 2 is mounted to slide on guide rods 3, 3. In setting up the press for operation, a large number of alternating filter plates 4 and rings 5 are assembled on the rods 3, the rings and plates being set in liquid tight contact between the heads 1 and 2. As illustrated in Fig. 3, plates 4 comprise a central disc 4^c on each side of which are perforated discs 4^b, the whole covered by canvas blankets 4^e. As clearly appears in Figs. 1 and 4, the plates 4 and blankets 4^e have central apertures 4^d therethrough so that when liquid under pressure from pipe 7 is forced through the fixed head 1, the liquid passes through from one end of the

press to the other and percolates through the blankets 4^e in parallel, the solid material being retained within the rings 5. However, during this operation, a hydrostatic pressure is exerted against the heads 1 and 2 which is resisted by the rods 6, 6. These rods have nuts 6^a at one end cooperating with the fixed head 1 and at the other end rods 6 are provided, according to my invention, with extension heads 8, preferably threaded to the rods 6. The heads 8 extend through apertured bosses 2^a on the movable head 2 and are provided with vertical slots or apertures 9 for receiving keys 10, which normally engage the outer face of the bosses 2^a and sus-

tain the tension in the rods 6. Heads 8 are preferably threaded to the rods 6 but may be otherwise secured thereon if desired. The openings in the bosses 2^a are of suitable size 5 to permit the ready insertion and removal of the heads 8, preferably the keys 10 have parallel sides throughout their active faces and have an overhanging lip 10^a at one end to prevent their falling through the apertures 9 when dropped therein. The workmen may therefore drop the keys in these 10 apertures without further thought. The keys 10 may also be secured to the head 2 by means of chains or other tie members if desired. 15

When the spaces between adjacent plates 4 have been filled by the solid material, the 20 movable head is forced toward the fixed head by means of a piston rod 11 secured to a piston, not shown, contained in a cylinder 12 (Fig. 1^a). This action of the piston rod and piston is controlled by the lever 13, which operates the valves regulating the inlet and outlet of fluid to cylinder 12. When 25 the tension on rods 6 has thus been relaxed by the piston rod 11, the keys 10 may be readily withdrawn from the slots 9 and heads 8, and the nuts 6^a relaxed. The action of the piston rod 11 is thereupon reversed and the movable head 2 withdrawn 30 from head 1 along rods 3 sufficient to permit the ready removal and cleaning of the plates 4 and rings 5. After cleaning the plates and rings are re-assembled as shown, 35 pressure is exerted on the head 2 by piston rod 11, the keys 10 replaced in the position illustrated in Fig. 1 and the nuts 6^a are tightened to insure a liquid tight joint between the plates 4 and rings 5. Pressure

on piston rod 11 is otherwise relaxed and the 40 apparatus is ready for another run.

It will be seen that by means of my arrangement of keys cooperating with the tension rods of the press that the press may be 45 operated with a maximum speed and convenience and that it may also be designed with a minimum number of tie-rods 6, thus reducing the number of parts and the cost of manufacture of the press.

It will be seen, moreover, that by threading the extension heads 8 to the rods 6, the rods may be used with an ordinary type nut provided at any time it should become necessary to do so owing to theft of the keys 10 or accidental destruction of them. 50

It will be understood also that I may use the construction according to my invention on the ends of tie-rods at the fixed head of the machine if desired, without departing from my invention, and that I do not limit myself to the form of slotted head with key described herein, as I may use other forms of interlocking heads and keys within my invention. 55

Having thus described my invention, I 60 claim:

A filter press comprising in combination a fixed head, a movable head, tie-rods extending between said heads, extension heads 70 threaded on said tie-rods at the end of the rods co-operating with said movable head, said extension heads having slots therethrough and keys for said slots normally co-operating with the outer face of said movable head for transmitting the thrust from 75 said head to said tie-rods

ALANSON McD. GRAY.
